CORE CATCHER

John H. Howard, Huntington Park, Calif., assignor to Globe Oil Tools Company, Los Nietos, Calif., a corporation of California

Application May 19, 1933, Serial No. 671,889

3 Claims. (Cl. 255—72)

This invention relates to a device for use in well drilling operations and relates more particularly to a core catcher for use in a core drill or core receiving well bit. It is a general object of the present invention to provide a simple, practical core catcher that is dependable in operation.

One type of core catcher that has gone into general use involves gripping members or slips that are actuated inwardly into gripping engagement with the core through cooperation with an inclined internal shoulder in the core drill. The active cooperation of the gripping slips with the inclined shoulder of the drill is caused by longitudinal movement of the core catcher relative to the body of the drill. The pitch or inclination of the slip actuating inclined shoulder on the interior of the drill is usually comparatively slight so that the slips may be actuated inwardly with sufficient force to properly grip the core. In assembling or making up the drilling string when a core drill is being run into the well, it is necessary to set or suspend the string on the slips in the rotary table each time a stand of drill pipe is added to the string. The jarring action to which the drilling string is subjected each time the string is set on the rotary table slips, jars or forces the core catcher downwardly so that its slips or gripping members are forced inwardly through cooperation with the inclined shoulder on the interior of the drill. In many instances, this downward movement of the core catcher causes the slips to move downwardly on the inclined shoulder a considerable distance so that the core catcher becomes immovably wedged on the inclined shoulder and when the drilling operation is started, the upper end of the core passes upwardly into the caught or wedged core catcher. The upper end of a core is often rounded or reduced in size and may pass upwardly between the contracted slips of the core catcher, thus increasing the friction between the slips and the inclined shoulder so that the core catcher cannot move upwardly to allow the core to freely enter the core barrel.

An object of this invention is to provide a core catcher that cannot become wedged in the core drill or made inoperative by the jars or shocks to which it may be subjected when the core drill is being run into the well.

Another object of the invention is to provide a core catcher including slips or gripping members operable inwardly to grip a core and means for holding the gripping members outward or unactuated until the core has entered the core catcher.

Another object of the invention is to provide a

simple, practical and effective means for holding the slips or gripping members of a core catcher against inward movement until the core enters the core catcher or approaches the core catcher.

Another object of the invention is to provide a core catcher including core gripping members and means for holding the gripping members against premature or undesirable contraction or actuation that does not interfere with the free passage of the core into the barrel or with the proper or timely operation of the gripping members.

Another object of the invention is to provide a means for holding the core gripping members of a core catcher extended or unactuated until the core enters the core catcher, that may be used with various forms of core catchers and that does not require the alteration or modification of the core catcher or core drill.

Another object of the invention is to provide a simple, inexpensive member or structure adapted to be positioned within the series of gripping members of a core catcher that has a releasable or frangible connection with the core catcher, which connection is released or broken when the core enters the core catcher, allowing the said member or structure to be forced upwardly into the core barrel so that the core catcher may be actuated in the usual manner when desired.

Another object of the invention is to provide a means or device for holding the gripping slips or members of a core catcher against premature operation, that may be easily and quickly positioned or mounted in the core catcher.

A further object of the invention is to provide a core catcher including slips operable into gripping engagement with a core upon relative longitudinal movement between the core drill and core catcher and a means for holding the core catcher against longitudinal movement relative to the drill, said means being releasable by a core entering the core catcher.

Further objects and features of the invention will be best and fully understood from the following detailed description of typical forms and applications of the invention, throughout which description reference is made to the accompanying drawing, in which:

Fig. 1 is a side elevation of a typical core drill with the lower portion appearing vertical cross section to illustrate one form of the present invention arranged in the drill. Fig. 2 is an enlarged bottom plan or elevation of the core catcher illustrated in Fig. 1. Fig. 3 is a vertical detailed sectional view of another form of the invention, and Fig. 4 is a top or plan view of the means

embodied in the form of the invention illustrated in Fig. 3 for releasably holding the slips against operation.

In accordance with its broader aspects, the present invention may be embodied in or carried out in connection with core catchers for use in various kinds of core drills and core catchers varying considerably in construction, design, etc. Throughout the following detailed disclosure, I will describe two typical forms or applications of the invention for use in a more or less typical core drill, it being understood that the invention is not to be construed as limited or restricted to the specific details about to be set forth, but is to be taken as including any features or modifications that may fall within the scope of the claims.

The core drill illustrated in Fig. 1 of the drawing includes, an outer barrel 10 provided at its upper end with a sub 11 for facilitating connection of the drill with the drilling string. A sub 12 is provided on the lower end of the outer barrel 10 and carries a sub or tubular member 13 in which the core catcher operates. An inner barrel 14 is provided within the barrel 10 to receive the core. The lower end portion of the core barrel or inner barrel 14 is threaded into the member 13 and its lower end forms a downwardly facing shoulder 15. A tubular or annular bit head 16 is provided on the lower end of the member 13 and carries spaced cutting parts or blades 17. The cutting blades 17 are operable to make an annular cut in the formation and thus form a core which may be received in the core barrel 14. A downwardly and inwardly inclined shoulder 18 is provided on the interior of the member 13 to actuate the gripping parts of the core catcher. The circulation fluid is passed downwardly between the two barrels 10 and 14 and is conducted downwardly through fluid passages 19 and 20 to discharge from the lower end of the bit head 16. As the present invention is not primarily concerned with the specific construction of the core drill the details described above are not to be taken as restricting the scope or application of the invention.

The core catcher illustrated in Figs. 1 and 2 of the drawing includes, generally, a body 21 shiftable longitudinally in the opening 22 of the member 13, gripping members or slips 23 carried by the body 21 and operable inwardly to grip a core through cooperation with the inclined shoulder 18, and means 24 for preventing premature or undesirable operation of the slips.

The body 21 of the core catcher is tubular, and is proportioned so that it may freely shift longitudinally in the opening 22 of the member 13. The central longitudinal opening 25 of the body 21 is adapted to receive or pass the core as it passes upwardly into the barrel 14. The upward movement of the body 21, relative to the core drill, is limited by the engagement of its upper end with the shoulder 15 as illustrated in Fig. 1 of the drawing. The downward movement of the body 21 relative to the drill is usually limited by engagement of the slips 23 with the inclined shoulder 18 as will be subsequently described.

The gripping members or slips 23 are operable inwardly into gripping engagement with a core through cooperation with the inclined shoulder 18 upon downward movement of the body 21 relative to the body member 13 of the drill. The slips 23 are attached to or suspended from the body 21 by flexible members or spring members 26. Any desirable or suitable number of circumferentially spaced slips 23 may be embodied in

the core catcher. The flexible members 26 extend through vertical or longitudinal grooves in the exterior of the body 21. The members 25 are attached to the body by rivets 28, or the like, extending through openings in the body, the flexible members 26 and blocks 27 seated in the grooves. The flexible members 26 project downwardly from the body 21 and the slips 23 are attached to the lower end portions of the members. The rear or outer sides of the slips 23 are inclined to have effective sliding engagement with the inclined shoulder 18. Grooves or notches 29 are provided in the outer sides of the slips 23 to receive the end portions of the flexible members 26. Rivets 31 attach the slips to the springs 26.

The inner faces of the slips 23 are serrated or toothed so as to dependably grip the core. The springs or flexible members 26 project upwardly from the body 21 and their projecting upper portions are bent or bowed inwardly so as to engage the core to resist movement of the core catcher relative to the core and to aid in gripping and supporting the core. During the drilling operation when the core is being received in the drill, the upper end portions 33 of the spring members 26 yieldingly engage the core to resist downward movement of the core catcher so that the body 21 of the core catcher is maintained in its uppermost position where its upper end engages the shoulder 15. When the core catcher is in the position just mentioned, the slips 23 are extended or unactuated. It will be apparent that when the drill is raised or moved upwardly that the upper portions 33 of the spring members 26 yieldingly engage the core to resist movement of the core catcher so that the gripping members or slips 23 are actuated inwardly against the core by the upwardly moving inclined shoulder 18.

The means 24 for preventing premature or undesirable operation of the gripping slips 23 holds the slips 23 in their fully out or unactuated positions until the core is received in the drill. By holding the gripping slips 23 outwardly in their unactuated position, the means 24 prevents downward movement of the body 21 of the core catcher. In the embodiment of the invention illustrated in Figs. 1 and 2 of the drawing, the means 24 includes an element or member 35 adapted to be arranged within the core catcher. The member 35 is provided to engage the inner sides of the slips 23 to positively prevent inward movement or contraction of the slips. In accordance with the broader principles of the invention, the member 35 may be of any suitable shape and the invention contemplates the construction or formation of the member 35 of any suitable material. The slip controlling member 35 may be made of wood, metal, a frangible material such as a ceramic product, or any other suitable relatively inexpensive material. In the particular case illustrated in the drawing, the slip controlling member 35 is formed of wood, and is in the nature of a cylinder or tube having a cylindrical exterior, and a central longitudinal opening 36.

The walls of the member 35 are of suitable thickness to have the desired strength. In accordance with the invention, the slip controlling member 35 is proportioned so that it holds the slips 23 outward against the walls of the opening 22 or against the extreme upper end portion of the inclined shoulder 18. In the particular proportioning and relating of parts illustrated in the drawing, the slips 23 are at the extreme upper end portion of the inclined shoulder 18 when

the upper end of the body 21 is in engagement with the shoulder 15, and the member 35 operates to hold the slips outwardly against the upper portion of the shoulder. As the control member 35 prevents inward movement of the slips 23, the body 21 is held against longitudinal movement relative to the body of the drill and the slips cannot move downwardly on the shoulder 18. The member 35 is rigid and sufficiently strong to dependably resist any tendency of the slips 23 to move downwardly on the shoulder 18 under the influence of the jarring action to which they may be subjected when the drill is run into the well.

The invention includes a releasable or frangible connection between the member 35 and the body 21 of the core catcher that holds the member 35 in its operative position during the running of the drill into the well and until a core is received in the drill. One or more connecting members or pins 38 extend through radial or transverse openings 37 in the body 21 and extend into the member 35. The pins 38 are in the nature of frangible pins or shear pins that are sheared off when the lower end of the member 35 engages a core during the drilling operation. In practice, the pins 38 may be in the nature of common nails passed through the openings 37 in the body 21 and driven into the member 35 or passed into already formed openings in the member. In the particular embodiment of the invention illustrated in the drawing, there are two pins 38 extending through diametrically opposite openings 37 in the body 21.

It is believed that the operation of the form of the invention illustrated in Figs. 1 and 2 of the drawing will be readily apparent from the foregoing detailed description. The member 35 may be assembled in the core catcher prior to the arrangement or assembling of the core catcher in the drill. The member 35 may be easily and quickly assembled in the core catcher and attached to the body 21 by means of the pins or nails 36. The control member 35 holds the slips 23 and the body 21 in the positions illustrated in Fig. 1 of the drawing when the drill is run into the well, and until a core is received in the drill. As described above, the member 35 is proportioned and related to the other parts so that it holds the slips 23 outwardly against the upper end portion of the inclined shoulder 18 thereby holding the entire core catcher against longitudinal movement in the drill. In this manner the member 35 prevents the slips 23 from being actuated inwardly through cooperation with the shoulder 18 by any jarring action to which the core catcher may be subjected when the drill is run into the well bore. When drilling is started the cutters 17 make an annular cut in the formation leaving a central core which is received in the tubular bit head 16. When the core is a certain length its upper end may be received in the opening 36 of the member 35 or the lower end of the member 35 may strike the upper end of the core. The upper end of the core may be considerably reduced in size in which case it may be received by the opening 36 of the member 35. As the core drill is fed downwardly during the drilling operation, the engagement of the member 35 with the core results in shearing of the pins 36 so that the member 35 is forced upwardly from between the slips 23 and finally entirely out of the core catcher. Upon the member 35 being forced upwardly out of engagement with the

slips 23, the slips are free to be actuated, however, the engagement of the member 35 with the upper portions 33 of the spring members holds the core catcher in the up position where the upper end of its body is in engagement with the shoulder 15. When the member 35 is finally forced out of engagement with the spring parts 33 the core takes its place so that the yielding engagement between the spring members 33 and the core maintains the core catcher in its up or unactuated position. When it is desired to remove the drill or break the core loose from the formation, the drill is raised or pulled upwardly and the engagement of the spring parts 33 with the core resists upward movement of the core catcher so that the inclined shoulder 18 moves upwardly relative to the slips 23 and forces the slips inwardly into tight gripping engagement with the core. When the member 35 is forced upwardly through the core catcher by the entering core, it is free to be supported on the upper end of the core and is readily received in the core barrel 14 so that it does not in any way interfere with the proper operation of the drill. Further, the slip controlling member 35, in being entirely free within the barrel 14 after leaving the core catcher, does not spoil or break up the core.

The embodiment of the invention illustrated in Figs. 3 and 4 of the drawing includes, generally, a body 21^a, slips 23^a connected with the body, and means 40 for preventing premature operation of the slips.

The body 21^a and slips 23^a may be identical with the corresponding parts of the form of the invention illustrated in Figs. 1 and 2 of the drawing. The slips 23^a are carried by spring members 41 attached to the tubular body 21^a. The spring members 41 have upper portions 42 for engaging the core to resist movement of the core catcher relative to the core. The inner sides of the slips 23^a are serrated or provided with teeth 44 for gripping the core. The outer sides of the gripping members or slips 23^a are inclined to slidably cooperate with the shoulder 18 of the drill.

The means 41 operates to hold the several slips 23 against actuation or inward movement until a core is received in the drill and passes upwardly between the slips. The means 40 includes a member having a part or arm 50 for engaging each slip 23^a. The slip controlling element or member is formed of a plurality of light rods or lengths of wire crossed and connected between their ends so as to form a plurality of radial arms 50. The lengths of rod or wire forming the arms 50 may be welded or otherwise connected together. The member consisting of the plurality of radial arms 50 is in the nature of a spreader or spider engaging the slips 23^a. Releasable connections are provided between the arms 50 and the slips 23^a. Horizontal sockets or openings 51 are provided in the inner sides of the gripping slips 23^a to receive the outer end portions of the arms 50. The openings 51 may be proportioned to more or less freely receive the end parts of the arms 50 so that the arms may be readily forced out of the openings when engaged by the core. The arms 50 may be bent or bowed downwardly and inwardly slightly as illustrated in Fig. 3 of the drawing.

It will be apparent how the slip controlling member may be assembled between the slips 23^a by springing the arms 50 into the openings or sockets 51. When the core drill is being run

into the well, the arms 50 of the slip controlling member hold the slips 23^a against inward movement and maintain them in positions against the upper portion of the shoulder 18 so that 5 the core catcher is held against longitudinal movement in the drill. As the core catcher is held against movement, the slips 23^a cannot be actuated or forced inwardly through the jars or shocks to which the drill may be subjected, 10 while being lowered or run into the well. In this manner the gripping slips 23^a are prevented from becoming wedged or set on the inclined shoulder 18. When the arms 50 or any one of the arms 50 is engaged by the upper end of 15 the core during the drilling operation, the arms are sprung or bent upwardly so that their outer end portions pull out of the openings 51. The slip controlling member is then held on the upper end of the core and enters the core barrel 14 as the drilling continues. The core catcher is operated in the same manner as the core catcher illustrated in Fig. 1 of the drawing. When it is desired to remove the drill or break 20 the core loose from the formation, the drill is raised and the inclined shoulder 18 cooperates with the slips 23^a to force them into gripping engagement with the core.

The present invention provides a core catcher that is dependable in operation and that is not 25 rendered imperative by the jarring action caused by assembling or making up the drilling string, as the drill is lowered into the well. The slip controlling member positively holds the slips outwardly and thereby limits or prevents longitudinal shifting of the core catcher in the drill. The 30 means for controlling the slips or for preventing premature actuation of the slips is simple and inexpensive of manufacture and does not in any way interfere with the proper operation of the core catcher or drill. The slip controlling member may be easily and quickly assembled in the 35 core catcher without modifying or altering the construction of any of the parts of the core catcher.

The flexible core engaging elements of the core catchers herein described and the manner in which they are secured to the core catcher bodies are claimed in the copending application of John H. Howard and Alfred C. Catland entitled 5 Core catcher, Serial Number, 661,482.

Having described only a typical form and application of my invention, I do not desire to be limited or restricted to the specific form and application above set forth, but wish to reserve 10 to myself any variations or modifications that may appear to those skilled in the art or fall within the scope of the following claims.

Having described my invention, I claim:

1. A core catcher for use in a core drill including, a body adapted to be arranged in the drill, a plurality of core engaging members carried by the body operable inwardly into engagement with the core, and means for holding the members against inward movement releasable 20 by the core, said means including an element engaging said members and releasably rigidly connected with the body.

2. A core catcher for use in a core drill including, a body adapted to be arranged in the drill, a core gripping slip carried by the body and operable inwardly to grip a core, and means for holding the slip against inward movement releasable by the core, said means including a member engaging the slip, and a frangible rigid 30 connection between the member and the body, whereby the member is disengaged from the slip upon engaging a core during the drilling operation.

3. A core catcher for use in a tubular core drill 35 having an inclined internal shoulder said core catcher including, a shiftable body in the drill, a plurality of circumferentially spaced gripping slips connected with the body and operable inwardly to grip a core, a member within the series 40 of slips operable to hold them against inward movement, and a shear pin rigidly connecting the member with the body.

JOHN H. HOWARD.
